Primary Examiner — Alison M Ofstun*(74) Attorney, Agent, or Firm* — John M. Lipchitz(57) **CLAIM**

The ornamental design for a shaving razor guard bar, as shown and described.

DESCRIPTION

FIG. 1 is a top perspective view of a shaving razor guard bar showing our new design;

FIG. 2 is a top view thereof;

FIG. 3 is a bottom view thereof;

FIG. 4 is a right view thereof;

FIG. 5 is a left view thereof;

FIG. 6 is a rear view thereof;

FIG. 7 is a front view thereof; and,

FIG. 8 is a top perspective view thereof, shown in an environment of use.

In FIGS. 1-7, the broken lines illustrate portions of the article and form no part of the claimed design. In FIG. 8 the broken lines illustrate environmental subject matter and form no part of the claimed design.
